(57) **CLAIM**

The ornamental design for a basket and back gates for a cart, as shown and described.

DESCRIPTION

FIG. 1 is a front perspective view of my new design for a basket and back gates for a cart.

FIG. 2 is a side elevation view of the right side, the left side being a mirror image thereof, of FIG. 1.

FIG. 3 is a front side elevation view of FIG. 1.

FIG. 4 is a back side elevation view of FIG. 1.

FIG. 5 is a top plan view of FIG. 1.

FIG. 6 is a bottom plan view of FIG. 1; and,

FIG. 7 is a front side elevation cut away view taken along line 7-7 of FIG. 2.

The features shown in broken lines in the drawing depict environmental subject matter only and form no part of the claimed design.
